TAMPER-PROOF INNER SEAL

James W. Wandell, Hoboken, N. J., assignor to
David N. Popik, escrowee

Application March 1, 1940, Serial No. 321,653

1 Claim. (Cl. 215—21)

This invention relates to new and useful improvements in a tamper-proof inner seal for containers.

The invention has for an object the construction of a seal as mentioned which is characterized by a cylindrical body having a top closure wall of slightly smaller diameter than said body, and adapted to be forced into the vertical neck of a bottle so that said top closure wall is slightly inwards of the mouth opening of the neck, and a novel arrangement of a protected valve for controlling the flow of liquid from the neck of the bottle, and preventing refilling.

Still further the invention contemplates the provision of an annular member mounted on the outer end of said body and having several outwardly projecting ribs connecting with and supporting said top closure wall.

Still further the invention contemplates making use of a ring supported in the top of the cylindrical body and beneath said annular member and having an upwardly directed inner shield flange which will prevent the insertion of a wire for the purpose of tampering with the valve previously mentioned.

Still further the invention contemplates constructing the various parts of said tamper-proof inner seal of Celluloid material or other transparent material which is slightly flexible so that the cylindrical body may be readily forced into position within the neck of the bottle.

The invention also contemplates constructing the side walls of the cylindrical body with a slight taper to facilitate frictional engagement of the seal within the bottle neck.

For further comprehension of the invention, and of the objects and advantages thereof, reference will be had to the following description and accompanying drawing, and to the appended claim in which the various novel features of the invention are more particularly set forth.

In the accompanying drawing forming a material part of this disclosure—

Fig. 1 is a fragmentary enlarged vertical sectional view of the neck of a bottle provided with a tamper-proof inner seal constructed in accordance with this invention.

Fig. 2 is a plan view of the seal per se.

Fig. 3 is a horizontal sectional view of the seal only, taken on the line 3—3 of Fig. 1.

Fig. 4 is a horizontal sectional view of the seal only, taken on the line 4—4 of Fig. 2.

Fig. 5 is a sectional view similar to Fig. 1, but illustrating the neck of the bottle tilted as it would appear when its contents are being poured.

Fig. 6 is a vertical sectional view of the neck of a bottle of modified construction and provided with a tamper-proof inner seal according to this invention.

5 The tamper-proof inner seal, in accordance with this invention, includes a hollow cylindrical body 10 having a top closure wall 11 of slightly smaller diameter than said body and said body being adapted to be forced into the vertical neck 12 of a bottle so that said top closure 11 is slightly inwards of the mouth opening 12a of the bottle neck. More specifically, the outer face of the side walls of the body 10 is constructed at a slight taper, for example 2°, tapering from the top downwards. The body 10 may be constructed of Celluloid material, or other transparent material which has a slight "give" to facilitate its engagement in the neck of the bottle.

An annular member 14 is mounted on the outer end of the body 10 and has several outwardly projecting ribs 15 connected with and supporting the top closure wall 11. This top closure wall is of frusto-conical shape. Its top surface has a frusto-conical shaped recess 16.

25 A cylindrical peg 17 projects coaxially from the bottom of the top closure wall 11. A ring 18 is supported in the top of the cylindrical body 10 beneath said annular member 14 and has an upwardly directed inner shield flange 19. The ring 18 is supported by several ribs 20 extended along the inner face of the wall of the body 10. These ribs 20 extend the entire length of the body. The ring 18 merely sits upon the upper ends of the ribs 20. The ribs 15 of the annular member 14 30 extend over the edge portions of the ring 18, and engage the top face of the ring. It is these ribs (the ribs 15 and 20) which support the ring 18 in position.

The hollow cylindrical body 10 has a bottom 40 wall 21 which is provided with a valve seat 22. A valve 23 in the form of a small sphere of glass or other similar material normally rests upon the seat 22. This valve 23 is of a slightly larger diameter than the valve seat so that the valve 45 23 is securely held by the body 10. The inner edges of the ribs 20 serve to guide the valve 23 along the length of the body 10 when the bottle containing the inner seal is tilted, as indicated in Fig. 5.

50 The upper end of the hollow cylindrical body 10 is formed with a recessed shoulder 24. The bottom of the annular member 14 is formed with a corresponding recessed shoulder. These shoulders engage each other to properly align the annular member 14 upon the top of the cylind-

drical body 10. These parts are permanently connected by fusing or other means. A wax seal 25 is extended across the said top closure wall 11 and has edge portions 25^a which may be adhesively connected with the inner face of the bottle neck 12. This seal 25 may be engaged properly into position by a suitable hot die. The die forces the seal into place and the heat melts the wax which subsequently hardens and seals the neck of the bottle closed. The edge portions may also be turned downwardly as shown at 25^b and wrapped around the top closure wall 11. A conventional cap 26, and a cork or other material washer 27, is removably mounted upon the end of the bottle neck 12.

The operation of the device is as follows:

As illustrated in Fig. 1, the bottle is completely sealed. To remove the liquid contents of the bottle it is merely necessary that the cap 26 and washer 27 be first removed. Then with a sharp implement such as an ice pick, or pen knife, etc., the central portion of the seal 25 is ruptured by inserting said sharp instrument downwards into the conical recess 16. The instrument is then moved slightly laterally so as to engage a portion of the instrument beneath the seal 25. Then the instrument is lifted up to tear out the seal 25. The bottle having the neck 12 may now be tilted as illustrated in Fig. 5. The liquid contents will pass through the valve seat opening 22 of the body 10, then through the body 10, and will finally discharge from the space beneath the top closure wall 11. Since the bottom of the closure wall is of conical shape the liquid will discharge in a smooth stream.

When the bottle is in a vertical or substantially vertical position, the valve 23 will automatically engage the seat 22 due to gravity. This prevents refilling. It is not possible to insert a wire or other small implement through the space between the top closure wall 11 and the inner face of the bottle neck 12 and reach the valve 23 to unseat it, because such wire or implement will strike the ring 18 and be arrested by the upwardly directed flange 19.

The flange 19 will also cause the flow of the fluid to concentrate or converge toward the center

and abut against the bottom conical surface 11' of the closure wall and from this conical surface, the liquid will continue to flow out of the container in a smooth, even stream.

5 In Fig. 6 another application of the invention has been disclosed. In this application the tamper-proof seal is engaged quite a distance down in the neck 12' of a bottle. A cork stopper 28 is then engaged into the outer end of the neck of the bottle to seal it. This bottle may be emptied by first withdrawing the cork stopper 28 with a cork screw or other implement, and then the operation of the device is substantially identical to the previous form.

15 While I have illustrated and described the preferred embodiments of my invention, it is to be understood that I do not limit myself to the precise constructions herein disclosed and the right is reserved to all changes and modifications coming within the scope of the invention as defined in the appended claim.

Having thus described my invention, what I claim as new and desire to secure by United States Letters Patent is:

25 A tamper-proof inner seal for containers, comprising a tubular body member having an upwardly directed valve seat in its lower end, a ball inside said body member for engaging said seat, a plurality of axially-extending, circumferentially spaced ribs on the inside face of said body member for guiding said ball, the upper ends of said ribs terminating short of the upper end of said body member, a ring fitting within the upper end of said body member and resting on the upper 30 ends of said ribs, said ring having an upwardly directed flange on the inner periphery thereof and forming an annular trough, and a cage member comprising a top shield, substantially disc-like in plan view and supported above the top end of said body member in spaced relation thereto, and a plurality of downwardly projecting, circumferentially-spaced supporting posts engaged into said trough, said body member, ribs, ring, shield and posts being fused to one another 35 whereby to form an integral unit.

JAMES W. WANDELL.
